to The Hydraulic Development Corp., Inc., Wilmington, Del., a corporation of Delaware

Application March 2, 1939, Serial No. 83,295

Term of patent 7 years

To all whom it may concern:

Be it known that I, Johan A. Muller, a citizen of the United States, residing at Mount Gilead, in the county of Morrow and State of Ohio, have invented a new, original, and ornamental Design
For a Press, of which the following is a specification, reference being had to the accompanying drawing, forming a part thereof.

In the drawing:

Figure 1 is a front elevational view of a press
showing my new design;

Figure 2 is a side elevational view thereof.

I claim:

The ornamental design for a press, substantially as shown.

JOHAN A. MULLER.
